PROCESSING PHOTOGRAPHIC SENSITIZED MATERIAL

Rupert H. Draeger, United States Navy

Application December 24, 1935, Serial No. 55,976

16 Claims. (Cl. 95—98)

(Granted under the act of March 3, 1883, as amended April 30, 1928, 370 O. G. 757)

This invention relates to an apparatus for and a method of processing photographic sensitized strip material and more particularly of processing photographic paper in long strips. A convenient apparatus for carrying out this method is a tank into which is fitted a spiral holder and means to circulate the processing liquid transversely between the convolutions of the spiral.

The processing of photographic paper may be divided into three general methods:

First, that of processing the prints individually, in which case each print is handled separately through the various steps, including developing, fixing, washing and finally drying. This method of processing photographic prints requires the maximum of handling and is therefore apt to be the most expensive method.

A second method of processing photographic paper is to run it in a continuous strip through a processing machine in which the film or paper passes over a series of guide rollers, immersing it successively in the several processing solutions and finally pass it through some form of drying apparatus.

This method of photographic processing is rapid and adapted to processing in large quantities at a low cost. One disadvantage of this method is that a small quantity of film or paper cannot be processed at a low cost, due to the fact that large quantities of processing solutions are needed to fill the large tanks. Another disadvantage is the need for a leader to keep the machine threaded and still others are the large space occupied by the machine and its cost of construction.

The third method of photographic processing is the using of some form of holder that carries a quantity of film or paper in a compact form in which it may be placed in the various processing liquids.

As is well known, motion picture film may be processed readily in a holder of spiral form as described in U. S. Patent No. 1,170,576 or in my pending application Serial No. 49,756. Such a spiral holder may be used for photographic film or paper of narrow widths. When film or paper of more than a few inches in width is placed on this holder there is a tendency for the material to soften and the convolutions of the spiral to touch each other preventing even processing. This is especially true of light weight film or paper or fine paper made from linen rags. The execution of this method is, however, by no means limited to the employment of a spiral holder for handling the long strips of paper or film; any

device which holds the material in a compact form and substantially on edge being satisfactory. The material might be so held by winding it back and forth between the teeth of two spaced combs.

Regardless of the type of holder used, if a wide strip of paper, that is, over a few inches wide, is held in a small space, the coils or folds will touch and often stick so that they will not be processed properly if no effort is made to keep them separated.

The method of this invention includes circulating the liquids between the portions of material being processed thus keeping them free. If a spiral or other holder having the width of the strip material extending upward from it is used, the circulation may be produced by a rotating propeller in the tank below the holder.

In the accompanying drawings which illustrate an apparatus for carrying out this method, like numbers refer to like parts and

Fig. 1 is a sectional elevation of the assembled apparatus showing a spiral holder with paper mounted therein.

Fig. 2 is a plan view of the portion below line 2—2 of Fig. 1.

Fig. 3 is an elevation, partly broken away, of a slightly modified form of apparatus.

Fig. 4 is a partial plan view of the portion below line 4—4 of Fig. 3.

Fig. 5 is a plan view of the annular weight, also shown in Fig. 1.

In Fig. 1 is shown an open circular tank 10, having an inlet pipe 11, an overflow pipe 12, a stop-cock drain 13, and a stuffing box 14 through which is mounted a shaft 15 having a propeller 16 detachably secured to the inner end and a pulley wheel 17 secured to the outer end of said shaft. The electric motor 18 is connected to the pulley wheel 17 by means of a belt 19 and is geared down in such a manner that the propeller 16 is turned slowly.

Within tank 10 is removably mounted a cylinder 20 having an open bottom formed of radially extending vertical blades 21 secured to a ring 22 at their inner ends and to the bottom of cylinder 20 at their outer ends. The upper edge of cylinder 20 has a narrow outwardly turned flange 23. The space between cylinder 20 and the tank 10 is divided into vertical sections by means of spacers 24 which are held in position at the top by being secured to ring 22 and at the bottom by radially extending vertical blades 25 which in turn are secured to the central ring 27. The internal cylinder 20 is supported by the bearing of flange 23 on ring 22. The two internal struc-

through said open ended cylinder and between portions of said photographic strips, said fluid flow causing means comprising a pair of sets of radially extending vertical blades at one end of 5 said cylinder, a propeller rotating between said sets of blades, said photographic strip supporting means being located within said open ended cylinder, said strip supporting means supporting photographic strip at one edge, said photographic strip being held in vertical position by the vertical 10 flow of fluid between the portions thereof.

9. A photographic strip processing device comprising a tank adapted to contain a definitely limited quantity of processing fluid, an open ended cylinder within said tank spaced from the bottom and sides thereof, means for supporting photographic strips edgewise within said cylinder, means for causing a current of processing fluid to flow vertically upwardly through said open ended 15 cylinder and return through the space between the cylinder and the tank, said fluid flow causing means comprising a pair of sets of radially extending vertical blades at the bottom end of said cylinder, a propeller rotating between said sets of blades, said photographic strip supporting means resting on said radially extending blades within said open ended cylinder, and photographic strip material resting 20 on its lower edge on said strip supporting means, said photographic strip being held in vertical position by the upward flow of the processing fluid 25 between the portions thereof.

10. A photographic strip processing device comprising a containing means for a definitely limited quantity of processing fluid, means for supporting photographic strips edgewise within said processing fluid containing means, and means for continuously flowing and reflowing a non-swirling current of the processing fluid between said photographic strips.

40 11. A photographic strip processing device comprising a containing means for a definitely limited quantity of processing fluid, means for supporting photographic strips edgewise within said processing fluid containing means, and means for continuously flowing and reflowing a non-swirling current of the processing fluid between said photographic strips, said last mentioned means causing the current to enter between said photographic strips at the supported edge, whereby 45 said flowing current maintains said strips out of contact with each other.

12. A photographic strip processing device comprising a containing means for a definitely limited quantity of processing fluid, means for supporting a photographic strip at its bottom edge within said processing fluid containing means, and means for continuously flowing and reflowing a current of the processing fluid vertically upwardly along the photographic strip, said means causing the current to travel along the photographic strip, commencing at the supported bottom edge, said photographic strip being maintained in a vertical direction by the vertically flowing current.

65 13. A photographic strip processing device comprising a processing fluid containing means, means for supporting a photographic strip in spiral formation at one edge thereof within said processing fluid containing means, and means for flowing a current of the processing fluid between

the convolutions of the photographic strip from the supported edge to the other edge, whereby said flowing current maintains the surfaces of adjacent convolutions out of contact with each other.

5 14. A photographic strip processing device comprising a tank for containing a definitely limited quantity of processing fluid, an open ended cylinder within said tank spaced from the bottom and sides thereof, means for supporting photographic strips within said cylinder, means for 10 causing a current of processing fluid to flow vertically upwardly through said open ended cylinder and return through the space between the cylinder and the tank, said fluid flow causing means comprising a pair of sets of radially extending vertical blades at the bottom end of said cylinder, a propeller rotating between said sets of blades, said photographic strip supporting means resting on said radially extending blades within said open ended cylinder, and photographic strip material 20 resting on its lower edge on said strip supporting means, said photographic strip being held in vertical position by the upward flow of the processing fluid thereby, and means contacting with the upper edge of said photographic strip material 25 holding said photographic strip material in position against the flow of the processing fluid.

30 15. A photographic strip processing device comprising a tank, an open ended cylinder within said tank spaced from the bottom and sides thereof, means for supporting photographic strips within said cylinder, means for causing a current of processing fluid to flow vertically through said open ended cylinder, said fluid flow causing means comprising a pair of sets of radially extending vertical blades at the bottom end of said cylinder, a propeller rotating between said sets of blades, said photographic strip supporting means resting on said radially extending blades within said open ended cylinder, and photographic strip material 35 resting on its lower edge on said strip supporting means, said photographic strip being held in vertical position by the upward flow of the processing fluid thereby, and means contacting with the upper edge of said photographic strip material 40 holding said photographic strip material in position against the flow of the processing fluid, said contacting means comprising a spider shaped weight.

45 16. A photographic strip processing device comprising a tank for containing a definitely limited quantity of processing fluid, an open ended cylinder, means for supporting said open ended cylinder within said tank and spaced from the sides thereof, said means including a plurality of vertical fins extending from the outer side of said cylinder and a pair of sets of radially extending vertical blades secured at the bottom of said cylinder, a propeller rotatable between said sets of pairs of blades, causing a current to flow through said 50 cylinder and return between said vertical fins, said vertical blades causing the current to travel vertically in a non-swirling direction, and means for supporting photographic strip material on 55 edge within said open ended tank, whereby said vertically flowing fluid will maintain the portions of the photographic strip material out of contact with each other.
